UNITED STATES PATENT OFFICE.

CARL H. KNUDSEN, OF BROOKLYN, NEW YORK.

INTERNAL-COMBUSTION ENGINE.

1,253,481.

Specification of Letters Patent. Patented Sept. 21, 1920.

Application filed May 7, 1919. Serial No. 295,385.

To all whom it may concern:

Be it known that I, CARL H. KNUDSEN, a citizen of the United States, and residing at Brooklyn, in the county of Kings and State of New York, have invented certain new and useful Improvements in Internal-Combustion Engines, of which the following is a specification, such as will enable those skilled in the art to which it appertains to make and use the same.

This invention relates to internal combustion engines and particularly to what are known as fuel oil engines of this class which are designed to be used for marine purposes; and the object of the invention is to so construct the engine as to produce low compression and high speed and also to simplify the construction of the engine thus reducing the cost of the manufacture of the same; a further object of the invention being to provide a two-cycle V-type engine having a single combustion chamber and one of the cylinders being adapted to act as an exhaust port, while the other or opposite cylinder acts as an intake or scavenger port; and a further object being to provide the combustion chamber of the engine with an internal hot tube having a large heat radiating circumference, and which is so constructed as to permit the free expansion and contraction thereof and which will produce a proper combustion of the fuel mixture charged into the combustion chamber; and with these and other objects in view the invention consists in an engine of the class and for the purpose specified, constructed and operating as hereinafter described and claimed.

The invention is fully disclosed in the following specification, of which the accompanying drawings form a part, in which the separate parts of my improvement are designated by suitable reference characters in each of the views, and in which:

Fig. 1 is a perspective section of my improved engine, the section being on the line 1-1 of Fig. 2;

Fig. 2 a side view of the engine looking in the direction of the arrow 2 of Fig. 1;

Fig. 3 a partial section on the line 3-3 of Fig. 1;

Fig. 4 a plan and sectional view;

Fig. 5 a diagrammatic view of the gear construction which I employ;

Fig. 6 a detail view of a hot tube which

I employ, with part of the construction broken away and in section; and,

Figs. 7 and 8 are detail sectional views of a modified form of hot tube and cylinder head construction.

In Figs. 1 to 4 inclusive, I have diagrammatically illustrated four cylinders or two sections of my improved engine and have shown at 10 the main shaft thereof, and at 11 and 12 crank shafts arranged on opposite sides of the main shaft. Mounted centrally of the main shaft is a large gear 13 having two gear faces 13^a—13^b, the teeth of which are arranged at different angles and two smaller gears 14 and 15 are mounted on the shafts 11 and 12 and each provided with two gear faces 14^a—14^b, 15^a—15^b, the teeth of which are arranged in the same manner as the teeth of the gear faces 13^a—13^b and are adapted to operate in connection therewith, and the gears 13, 14 and 15 are preferably inclosed in a housing 16.

The engine as shown in the drawing comprises two sets of V-type cylinders, each set of which comprises cylinders 17 and 18 joined or connected at the top by a cylinder head 19, and connected with the bottom of the cylinders 17 and 18 respectively are crank cases 20 and 21 through which the crank shafts 11 and 12 pass.

The cylinders 17 and 18 are provided with water jackets as shown at 22 through which water for cooling purposes is adapted to pass, said water being supplied to said water jackets through pipes 23 and discharged therefrom through pipes 24, as clearly shown in Figs. 1 and 2. The cylinder 17 is provided with an air chamber or jacket 25 placed in communication with the crank case 20 as shown at 26, and in communication with the crank case 21 through a bypass tube 27 having air inlet controlling valves 28.

The cylinder 17 forms the intake or scavenger port of the engine, said cylinder being placed in communication with the crank cases 20—21 and the chamber or jacket 25 through ports or passages 29, and the cylinder 18 forms the exhaust port through which combustion products may pass out into and through an exhaust manifold 30 through ports or passages 31.

It will be noted that the shaft 10 is supported centrally between the crank cases 20 and 21 in bearings 32, while the crank shafts 11

11 and 12 are mounted in bearings 33 in the crank cases 20 and 21, and one end of the shaft 12 is provided with an air compressor mechanism 34 of the usual or any preferred 5 form and construction, while the opposite ends of the crank shaft 11 are provided with fuel oil pumps 35 which are also made of the usual or any preferred construction.

Mounted in each of the cylinder heads 19 10 are approximately V-shaped hot tube devices 36 shown in detail in Fig. 6, and comprising a downwardly directed tube 37 and upwardly and outwardly directed tubes 38. All of said tubes are connected with a Y- 15 coupling 39 and the upper ends of the tubes 38 extend outwardly through the opposite sides of the cylinder head 19 as shown at 40 and are secured to said head in any desired manner. In Fig. 1 of the drawing I have 20 diagrammatically indicated at 41 a burner device which is designed to heat the hot tube device 36 in starting the engine in the usual manner as hereinbefore described.

Connected centrally of the top of the cylinder head 19 is a fuel supply device 42 25 placed in communication with the air compressor 34 through a pipe 43 and in communication with one of the oil pumps 35 through a pipe 44, and said supply device 30 42 is designed to charge or spray the fuel mixture into the combustion chamber 45 in the cylinder head 19 at the top of the cylinders 17 and 18, which mixture is ignited by the hot tube construction 36 in the usual 35 manner.

Movably mounted in the cylinders 17 and 18 are pistons 46 and 47 having connecting rods 48 and 49 mounted on the cranks of the crank shafts 11 and 12, as will be readily 40 understood, and it will also be understood that while I have used the singular in describing the cylinder and crank case construction and the various parts connected therewith, each series of pairs of cylinders 45 will be constructed in the same manner, and while I have shown but two sets of cylinders in the accompanying drawing it will be apparent that any desired number or pairs of cylinders may be coupled up end to 50 end and geared in connection with each other in the manner shown and described herein.

The operation of the engine will be 55 readily understood from the foregoing description when taken in connection with the accompanying drawing and the following statement. In the position of the pistons 46 and 47 in the cylinders 17-18, as shown in Fig. 1 of the drawing, air in the crank cases 20 and 21 is free to pass through the chamber or jacket 25, ports or passages 29 into the cylinder 17 through the combustion chamber 45, cylinder 18 and out through the ports or passages into and 65 through the exhaust manifold 30 to clean

out the previously charged fuel, and in the upward movement of the pistons 46-47 in the cylinders 17-18 fuel is supplied to or introduced into the combustion chamber 45 through the devices 42, and said fuel is compressed as the pistons continue their upward movement and ignited or combusted by the hot tube construction 36 thus moving the pistons downwardly into the cylinders, and the construction or location of the 75 ports 29 and 31 in said cylinders will be such that the ports 31 will open before the ports 29 to permit the gases and air to be discharged out through the manifold 30, and this operation is aided by the scavenger 80 action hereinbefore set out.

It will also be apparent that in the upward movement of the pistons, air will be sucked into the crank cases 20-21 through the valves 28 and the downward movement 85 of said pistons will close said valves automatically and force the air in the crank cases 20-21 upwardly into and through the cylinders as hereinbefore set out.

My invention produces an engine of the 90 class specified which is very simple in design and construction and efficient in operation, the internal hot tube construction employed producing a large heat radiating area which will readily charge the fuel or 95 produce a perfect combustion of the fuel supplied to the engine and also an improved scavenger action which will properly clean out the cylinders and combustion chamber, after each firing stroke. 100

In Figs. 7 and 8 of the drawing I have shown at 50 a modified form of cylinder which may be substituted for the cylinder head 19, and at 51 a modified form of hot tube construction comprising a tube or 105 sleeve 52 adapted to pass centrally and transversely through the combustion chamber 53 in the cylinder head 50 and held in place by rings 54 at the opposite sides of the cylinder head 50. The opposite end 110 portions of the tube or sleeve 52 are provided with internal ring members 55 composed of fire-brick or similar material.

It will be understood that the hot tube device 51 shown in Figs. 7 and 8 will be 115 heated by a torch or other device in the usual manner in the starting of an engine, after which the heat of the products of combustion will keep said tube at the desired 120 temperature, this being also true of the hot tube construction 36 hereinbefore described, and while I have shown certain details of construction for carrying my invention into effect, it will be understood that various 125 changes therein and modifications thereof may be made, within the scope of the appended claims, without departing from the spirit of my invention or sacrificing its advantages.

Having fully described my invention, 130

what I claim as new and desire to secure by Letters Patent, is—

1. An engine of the class described comprising oppositely arranged cylinders, a cylinder head connected with the tops of said cylinders and placing the same in communication through a combustion-chamber, crank cases at the bottom of each of said cylinders, a main shaft mounted centrally 10 of and between the crank cases, crank shafts at the opposite sides of said main shaft and adapted to pass through and operate in said crank cases and geared in connection with the main shaft, and a V-shaped hot tube 15 construction mounted in the combustion chamber of the cylinder head.
2. A V-type engine of the class described comprising oppositely arranged cylinders, a cylinder head having a combustion chamber placed in communication with each of 20 said cylinders, crank cases at the bottom of said cylinders, a by-pass port or passage for placing said crank cases in communication, one of said cylinders being provided 25 with a plurality of intake ports or passages in communication with one of the crank cases and the other of said cylinders with exhaust ports or passages, pistons mounted in said cylinders and adapted to control the 30 passage of air into one of said cylinders through said intake ports or passages and out through the other of said cylinders through said exhaust ports or passages, and a V-shaped hot tube construction mounted 35 in the combustion chamber.
3. A V-type engine of the class described comprising oppositely arranged cylinders, a cylinder head having a combustion chamber placed in communication with each of 40 said cylinders, crank cases at the bottom of said cylinders, a by-pass port or passage for placing said crank cases in communication, one of said cylinders being provided 45 with a plurality of intake ports or passages in communication with one of the crank cases and the other of said cylinders with exhaust ports or passages, pistons mounted in said cylinders and adapted to control the passage of air into one of said cylinders 50 through said intake ports or passages and out through the other of said cylinders through said exhaust ports or passages, a V-shaped hot tube construction mounted in the combustion chamber, a fuel mixture supply device connected with the cylinder head, and means for supplying air and fuel oil 55 under pressure to said device.
4. An engine of the class described comprising a plurality of cylinders arranged 60 in pairs, the separate pairs of cylinders being connected by cylinder heads having combustion chambers therein, crank cases at the bottom of each cylinder, crank shafts passing through said crank cases, a main 65 shaft, and means for gearing said crank shafts in connection with the main shaft.
5. An engine of the class described comprising a plurality of cylinders arranged in pairs, cylinder heads connecting the separate cylinders in each pair and provided 70 with a combustion chamber, a hot tube mounted in the combustion chamber of each of said cylinder heads, a fuel supply device mounted in said cylinder heads and in communication with the combustion chambers 75 therein, a main shaft mounted centrally of the engine and between the cylinders in each pair, crank shafts at the opposite sides of the main shaft and geared in connection therewith, and means whereby said crank 80 shafts will operate an air compressor and fuel oil pump devices to supply compressed air and fuel oil under pressure to said fuel supply devices.
6. An engine of the class described comprising a plurality of cylinders arranged in pairs, cylinder heads connecting the separate cylinders in each pair and provided 85 with a combustion chamber, crank cases at the bottom of said cylinders, a main shaft mounted centrally of the engine, crank shafts mounted on the opposite sides of the main shaft and passing through said crank cases, a gear mounted on the main shaft and provided with two gear faces the teeth of 90 which are arranged at different angles and other gears mounted on the crank shafts and each provided with two gear faces the teeth of which are arranged at different angles, and said last named gears being adapted to 95 operate in connection with the gear on the main shaft.
7. An engine of the class described comprising a plurality of cylinders arranged in pairs, cylinder heads connecting the separate cylinders in each pair and provided 100 with a combustion chamber, crank cases at the bottom of said cylinders, a main shaft mounted centrally of the engine, crank shafts mounted on the opposite sides of the main shaft and passing through said crank cases, a gear mounted on the main shaft and provided with two gear faces the teeth of 105 which are arranged at different angles and other gears mounted on the crank shafts and each provided with two gear faces the teeth of which are arranged at different angles, said last named gears being adapted to 110 operate in connection with the gear on the main shaft, means for admitting air into the crank cases, and means whereby the air from said crank cases may be passed into one of the cylinders of each pair and outwardly through the other cylinder of each 115 pair.
8. An engine of the class described comprising a plurality of cylinders arranged in pairs, the separate pairs of cylinders being 120 125

- connected by cylinder heads having combustion chambers therein, crank cases at the bottom of each of said cylinders, means for placing the crank cases of the separate pair 5 of cylinders in communication, means for admitting air to the crank cases, means for passing air from the crank cases into one of the cylinders in each pair and out through the other cylinders, and annular 10 exhaust manifolds around said last named cylinder through which the exhaust passes.
9. An engine of the class described comprising a plurality of cylinders arranged in pairs, the separate pairs of cylinders being 15 connected by cylinder heads having combustion chambers therein, crank cases at the bottom of each of said cylinders, pipes for placing the crank cases of the separate pairs of cylinders in communication, means 20 for admitting air to the crank cases, one of said cylinders in each pair being provided with an annular air chamber, a plurality of ports or passages for placing said annular air chamber in communication with the 25 bore of said cylinder, the other cylinders in said pair being each provided with annular exhaust manifolds having a common discharge, and a plurality of ports or passages in said last named cylinders for placing the 30 bores thereof in communication with said exhaust manifolds.
10. An engine of the class described comprising a plurality of cylinders arranged in pairs, the separate pairs of cylinders being connected by cylinder heads having combustion chambers therein, crank cases at the bottom of each of said cylinders, pipes for placing the crank cases of the separate pairs of cylinders in communication, means for admitting air to the crank cases, one of 35 said cylinders in each pair being provided with an annular air chamber, a plurality of ports or passages for placing said annular air chamber in communication with the bore of said cylinder, the other cylinders in said 40 pair being each provided with annular exhaust manifolds having a common discharge, a plurality of ports or passages in said last named cylinders for placing the bores thereof in communication with said 45 exhaust manifolds, and all of said cylinders and said exhaust manifolds being water-jacketed.

In testimony that I claim the foregoing as my invention I have signed my name in 50 presence of the subscribing witnesses this 3rd day of May, 1919.

CARL H. KNUDSEN.
